UNITED STATES PATENT OFFICE.

WILLIAM G. MEYERS, OF PHILADELPHIA, PENNSYLVANIA, AND FREDERICK E. COWARD, OF CAMDEN, NEW JERSEY.

DYNAMO-ARMATURE.

SPECIFICATION forming part of Letters Patent No. 389,894, dated September 25, 1888.

Application filed May 5, 1887. Serial No. 237,233. (No model.)

To all whom it may concern:

Be it known that we, WILLIAM G. MEYERS, of the city and county of Philadelphia, and State of Pennsylvania, and FREDERICK E. COWARD, of the city and county of Camden, and State of New Jersey, citizens of the United States, have invented new and useful Improvements in Armatures for Dynamo-Electric Machines, of which the following is a specification.

Our invention consists—

First, in an armature of a dynamo-electric machine, of semicircular metallic segments or otherwise suitably segmented plates mounted on guide-bars to form rings. The opposing ends of the semicircular segments are insulated from each other by air-spaces or by an insulating material.

Second, in an armature of a dynamo-electric machine, the combination of insulated guide-bars fastened to end plates and semicircular metallic segments or otherwise suitably segmented plates insulated from each other at their opposing ends and sides.

Third, in an armature of a dynamo-electric machine, of insulated semicircular metallic segments or otherwise suitably segmented plates mounted on insulated guide-bars, the openings between the opposing ends of each segment being out of line with the openings of the preceding and succeeding segments.

On reference to the accompanying sheet of drawings, making part of this specification, Figure 1 is a longitudinal and diametrical view of a hollow armature-core with sectioned ends for showing the construction and arrangement of the several parts. Fig. 2 is a view of the removable shaft. Fig. 3 is a reduced face view of the end plates. Fig. 4 is a reduced face view of the toothed semicircular segments, with insulating material between their opposing ends. Fig. 5 is also a reduced face view of the semicircular segments without insulating material between their opposing ends, and Fig. 6 is a reduced view of the guide-caps.

Similar letters refer to similar parts in the several views.

A is a removable shaft, and B are perforated end plates on its extremities.

C are carrying-bars, which center by their ends bearing in insulated openings a of the end plates, B.

D are thin semicircular metallic segments placed side by side on the carrying bars C, which pass through their insulated openings b, Figs. 1, 4, and 5. They are separated by insulating-washers E on the bars C, which make air-spaces e between them. Tooth-like elevations d are formed on periphery of each segment D for containing the wires, and they (the segments) are mounted on the carrying-bars C, so as to form rings, their opposing ends e held opposite to each other, and with a space, f, between the said opposing ends for air or any insulating material, Figs. 1, 3, 4, and 5. While the tooth-like elevations d are aligned, the spaces f between the opposing ends e of the segments are not in line, and do not form a continuous opening, f, the entire length of the segment series, but each opening f is out of line with the openings of the preceding and succeeding semicircular segments.

F are fan-blades fixed within the hollow of the armature to collars g', placed loosely on the shaft A and bolted to the end plates, B, or secured in any other manner that will cause them to turn coincidently with the shaft without being fixed to it. The shaft A passes snugly through a central opening, j, in each end plate, B, Figs. 1 and 3. Screw-threads k and 8c nuts l bind it to the other parts of the armature. By using a collar one of the screws can be dispensed with. The shaft can be withdrawn by loosening the nuts with a wrench passed into the neck m of either guide-bowl G without interfering with the structural combination of the armature.

The revolution of the armature causes its fans to keep up a continuous circulation of air in at the necks m of the guide-bowls G and the openings o of the end plates, B, and out through the openings or air-spaces e between the sides of the semicircular segments onto the wires wrapped in the depressions n, between the teeth d of the rings D of the armature, by which the temperature of the same is kept down.

The purpose of insulating the opposing

ends *e* of the semicircular segments is to effectually cut off all currents in the direction of rotation.

The semicircular segments are insulated at 5 their sides and opposing ends *e*, to cut off all longitudinal currents in the series of said semicircular segments.

If the openings *f* between the opposing ends *e* of the semicircular segments were in line, 10 they would divide the armature into two parts or halves, the consequence of which would be an abrupt change of the polarity of the armature. Therefore, in building up the armature, the said openings *f* are not arranged 15 in line, but each is out of line with the openings of the preceding and succeeding segments, by which is accomplished an even advance of magnetism in the armature as it is rotated within the influence of the field-magnets, thereby avoiding the abrupt change in 20 the polarity of the armature which would occur were the openings placed in line.

We have illustrated and described our invention by means of an iron plate or ring, *D*, 25 divided into two parts or halves or semicircular segments. Possibly it may be found convenient or necessary to divide the rings *D* into more than two segments. Therefore we 30 wish it distinctly understood that we do not confine ourselves to any given segmental partition of the rings *D*.

What we claim as our invention is—

1. In an armature of a dynamo-electric machine, semicircular segments or otherwise suitably segmented plates *D*, mounted on guide-bars to form rings, the opposing ends *e* of the segments being insulated from each other by air-spaces *f* or any insulating material, *g*, for the purpose shown and described. 35

2. In an armature of a dynamo-electric machine, the combination of insulated guide-bars *C*, attached to end plates, and semicircular segments or otherwise suitably segmented rings *D*, insulated from each other at their opposing ends *e* and sides, for the purpose shown and 40 described. 45

3. In an armature of a dynamo-electric machine, insulated semicircular segments or suitably segmented rings *D*, mounted on insulated guide-bars *C*, the openings *f* between the opposing ends *e* of each segment being out of 50 line with the openings of the preceding and succeeding segments, for the purpose shown and described.

WILLIAM G. MEYERS.
FREDERICK E. COWARD.
